BERTRAM SEITZ, OF PHILADELPHIA, PENNSYLVANIA

GATE FOR DELIVERY VEHICLES

Application filed September 1, 1928. Serial No. 303,378.

This invention relates to gates for delivery vehicles of the closed body type such as utilized by express and baggage concerns in transportation and delivery of small articles 5 or packages.

With the collapsible metallic lattice gates ordinarily employed heretofore on vehicles of the kind indicated, thieving was rendered comparatively easy incidental to cruising 10 about town and while the drivers were making deliveries, due to nonrigidity and flexibility of the gates: In other words, notwithstanding locking, the gates would yield to inward flexure at the top as well as outward flexure 15 at the bottom so that fairly large packages could be readily withdrawn.

The chief aim of my invention is to obviate the above contingencies through provision of a gate which is simple and inexpensive to 20 manufacture, sturdy though light in construction, absolutely rigid in locked position, and so devised as to afford variable access into the vehicle body in accordance with the size of the package to be withdrawn by the 25 driver.

Still other objects and attendant advantages will be manifest from the detailed description which follows when taken in connection with the attached drawings, wherein 30 Fig. I shows the rear of a closed vehicle body equipped with a closure gate conveniently embodying my invention.

Fig. II is a fragmentary plan section taken as indicated by the arrows II—II in Fig. I.

Fig. III is a detail sectional view taken as indicated by the arrows III—III in Fig. I.

Fig. IV is a view, similar to Fig. I, showing an alternative embodiment of my invention; and,

Fig. V is a detail section taken as indicated by the arrows V—V in Fig. IV.

With reference first more particularly to Figs. I—III of these illustrations, it will be observed that the form of gate there shown 45 is double, i. e. it embodies two components comprehensively designated 10, 10a which are separately hung at their remote edges to the closed vehicle body B by hinges 11, 11a so that their swinging edges meet when the gate 50 is in closed position. The gate components 10,

10a in turn comprise a multiplicity of subdivisions or sections 12, 12a—in the present instance two for each—which are inter-connected by hinges at 13, 13a so as to be swingable independently of each other. For the 55 sake of combined rigidity and lightness, the gate is preferably constructed from hardwood with spaced verticals 15, 16 and 15a, 16a joined by horizontals 17, 17a and diagonals 18, 18a to form the several sections. Inward movement of the gate components 10, 10a is limited by stops 19, 19a which are respectively secured to the upper ends of the meeting edge verticals 16, 16a at the back, and engage the top of the vehicle body B. These 60 stops 19, 19a are fashioned from flat bar metal and are offset as at 20—Fig. III—so that the gate closes flush with the back of the vehicle body B after the manner shown in 65 Fig. II.

To fasten the gate in closed position, I provide a securing means common to both components 10, 10a. This securing means includes a bolt 21 that is supported with capacity for axial sliding in strap bearings 22 attached to the edge vertical 16a of the gate component 10a, so as to be retractable from engagement with a socket 23 in the floor of the vehicle body B, the extent of lifting being limited by a stop shown at 24 in Fig. I. 70 The bolt 21 is also rotatable in the bearings 22, and at its upper end has a hasp-like wing 25 to engage the eye 26 of an associate fitting 27 secured to the edge vertical 16 of the gate component 10. With the parts 21, 27 of the 75 securing means in the position illustrated, a padlock 28 or the equivalent is applied to the eye 26 to prevent unauthorized opening of the gate when the vehicle is in motion and while deliveries are being made.

With the described arrangement, it will be apparent that by removing the padlock 28 and swinging aside the hasp wing 25 of the bolt 21 (without withdrawing the latter from the socket 23), the gate component 10 is freed 85 so that its sections 12 may be independently swung, or the whole swung about the hinges 11—all in accordance with the extent of access required to remove any particular package 90 from within the body B at the corre- 100

sponding side of the vehicle. If a greater degree of access is necessary, the bolt 21 is lifted with attendant freeing of the gate component 10a so that its sections can be swung likewise, either independently or together about the hinges 11a. The sectional construction of the gate is thus advantageous in that it admits of considerable time saving in withdrawing individual packages from the vehicle body, since only in the case of very large units need it be opened to the fullest extent. Moreover, by virtue of its rigidity and in view of the sturdiness of the novel securing means provided as hereinbefore explained, the gate cannot be flexed or forced when in locked position, the possibility of thieving being thus reduced to the very minimum.

The alternative embodiment of my invention shown in Figs. IV and V is identical to the first described in so far as the construction of the gate itself is concerned, and the same reference numerals have therefore been employed to designate the corresponding parts. In this case however, the securing means is somewhat different, i. e. both gate components 10, 10a are equipped with locking bolts 30, 31 adapted to respectively engage sockets 32, 33 in the floor of the vehicle body. The upward sliding motion of the bolts 30, 31 is limited by individually associated stops 34, 35 respectively on the meeting edge verticals 16, 16a of the gate components 10, 10a. The wings 36, 37 at the contiguous ends of the bolts 30, 31 are arranged to overlap. As shown, the wing 36 of bolt 30 is in the form of a hasp to engage over an eye 38 projecting from the wing 37 of the other bolt 31. A padlock 39 is employed as before to lock the gate in closed position, said padlock being applied to the protruding end of the eye 38, see Fig. V. The operation of the alternative embodiment is attended by advantages identical to those already pointed out in connection with the form featured in Figs. I-III, with the further advantage that the extra bolt 30 serves as a positive holding means for the gate component 10 incidental to manipulation of the companion gate component 10a.

Having thus described my invention, I claim:

1. A double gate for delivery vehicles comprising opposing components each including interhinged sections adapted to close with their swinging edges engaging, the meeting edges of the respective components carrying limiting stops at their upper ends offset to contact the top of the vehicle body so that the gate closes flush with the back end of said body.

2. A double gate for delivery vehicles comprising opposing components each including independently movable interhinged sections embodying spaced verticals joined by horizontals and diagonals, said sections being separately hinged to close with their swing-

ing edges engaging, and the meeting component verticals having attached flat-bar limiting stops at their upper ends offset to contact the top of the vehicle body so that the gate closes flush with the back end of said body.

3. A double gate for delivery vehicles comprising opposing components each including a multiplicity of independently movable interhinged sections, and embodying spaced verticals joined by horizontals and diagonals, said sections being separately hinged for independent opening or closure with their swinging edges engaging, and the meeting component verticals having attached flat-bar limiting stops at their upper ends offset to contact the top outer edge of the vehicle body so that the gate closes flush with the back end of said body.

In testimony whereof, I have hereunto signed my name at Atlantic City, New Jersey, this 30th day of August, 1928.

BERTRAM SEITZ.
